ATTORNEY.

UNITED STATES PATENT OFFICE.

EARL M. WITHERELL, OF DULUTH, MINNESOTA, ASSIGNOR OF ONE-HALF TO F. A. PATRICK & COMPANY, OF DULUTH, MINNESOTA, A CORPORATION OF MINNESOTA.

DRYING-FORM.

1,373,694.

Specification of Letters Patent.

Patented Apr. 5, 1921.

Application filed March 24, 1919. Serial No. 284,800.

To all whom it may concern:

Be it known that I, EARL M. WITHERELL, a citizen of the United States, residing at Duluth, in the county of St. Louis and State 5 of Minnesota, have invented certain new and useful Improvements in Drying-Forms, of which the following is a specification, reference being had therein to the accompanying drawing.

- 10 This invention relates to garment-drying forms and has special reference to novel means for holding a garment in position on the form while it is being dried and shaped.
- 15 The necessity for a device of this nature is well known to those versed in the art and the principal object of the present invention is to provide such means of simple construction and positive action and one that 20 may be readily applied to forms already in use.

Other objects and advantages of the peculiar construction will appear in the further description of the invention.

- 25 Drying forms referred to, upon which garments—such as mittens, gloves and hosiery—are placed for drying and shaping, are usually provided with a somewhat narrowed portion adjacent the base of the form 30 and which the open extremity of the garment surrounds after being placed upon the form. It is upon this portion that the holding means embodying the present invention is shown as applied.
- 35 Referring to the accompanying drawings forming part of this application and in which like reference characters indicate like parts:

Figure 1 is a side elevation of a fragmental portion of the lower end of a hollow perforated hosiery form with one form of 40 my present invention applied thereto,

Fig. 2 is a similar view of a modified form of holding device,

45 Fig. 3 is a similar view of still another modification of the device, and

Fig. 4 is a transverse sectional view on the line 3—3, Fig. 1.

- 1 represents the hollow metal form which 50 may or may not be perforated as desired. 2 represents a plurality of suitably spaced vertically disposed grooves or channels formed in the outer face of the walls of the form. These grooves may be any desired 55 length, and, as a preferred construction, have in their upper ends the concaved cups

or depressions 3, which are deeper than the remainder of the channels.

A thin metal band or collar 4 is shaped to snugly fit about the form 1 and has 60 rigidly fixed to the inner wall thereof the upstanding wire garment-holding members 5 which are so spaced as to register with and traverse the channels 2.

The extreme upper end of each holding 65 member 5 is bent inwardly toward the form, as at 6, then outwardly, forming the hook 7, the point of which extends slightly beyond the outer surface of the form 1, except when the holding members are in their 70 extreme uppermost position, with the backs 6 of the hooks nested in the cups 3, when they will be wholly back of a plane with the outer surface of the form.

When in this latter position the form is 75 ready for application of a garment thereto, which may be freely slid down over the hooks without engaging same.

The band 4 has formed upon its two opposed narrowest sides projections 8, by 80 which it is manually slid up and down upon the form and is made to fit snugly to establish the proper frictional contact therewith.

The holding members 5 are of spring wire and are so shaped as to at all times impinge 85 the bottom of the channels 2 when being reciprocated therein and thus increase the frictional contact of the holder and also insure the hooks at the ends thereof automatically springing into the depressions 3 90 of the channels when registering therewith and thus withdrawing from engagement with the garment being held.

In applying a garment to a form, both 95 hands of the operator are employed, one about each edge of the form and frictionally engaging the garment thereupon.

When the garment is thus being drawn down to its limits on the form, the lower edges of the hands of the operator will 100 naturally engage the extensions 8 of the band 4 and cause it to be depressed, thus forcing the hooks 7 outwardly into engagement with the garment and by which it is securely held after the application is completed.

In removing the garment, all that is necessary is to raise the band 4 until the hooks 7 enter the depressions 3, when they will be automatically withdrawn from engagement with the garment and the latter freed 110 to be removed in the usual manner.

While I have shown a depression at the upper ends only of the channels, into which the hooks on the ends of the wires recede, it is evident that there may be other parallel 5 rows of such depressions further down in the channels.

Such would be provided to accommodate different lengths of garments being dried and the hooks could be depressed in any set 10 desired to accommodate the garment.

It is further evident that the channels 2 might be formed in direct alinement with rows of the perforations 9 when applied to such forms. In this event the hooks 7 would 15 automatically recede into the perforations when made to register therewith and thus avoid the necessity of specially prepared depressions, such as illustrated at 3.

In Fig. 2 is illustrated a modified form 20 of holding means, comprising an upward extension of the band 10, which corresponds to the band 4, said extension being designated by the numeral 11.

The upper edge of this extension is of 25 serrated form, resulting in a plurality of tooth-like members 12 which are sprung inwardly to normally impinge the outer surface of the form and to automatically recede into the angular depressions 13 shaped 30 in the form and made to register therewith.

The apexes of the tooth-like members 12 are turned outwardly, forming suitable hooks 14 for engagement with the garment when placed upon the form and for holding 35 same in a like manner to the hooks 7, in the previously described embodiment of the invention. The depth of the apexes, of the recesses 13, is sufficient to allow the hook members to recede below a plane with the 40 outer surface of the form and to permit of the hooks 14 fully releasing themselves from the garment. The operation of this device is in all respects similar to the former.

45 In Fig. 3 is shown a modification of the shape of the channels 2, as shown in Fig. 1, such being for the simple purpose of contracting the sides of the open terminus and more permanently fixing the edge creases 50 of the garment being dried and shaped. For this purpose the channels 2 on either side of the centermost one, are curved outwardly and upwardly and may vary somewhat in their curvature, the ones nearest the 55 center being more curved than the others, so that less inwardly drawing stress is put upon the garment by the hooks farthest from the center of the form.

The wire members 5 being resilient, as 60 before described, will readily conform to and traverse the arcuate form of the channels.

In drying garments such as hosiery or the like, it is well known how unshapely the extreme edge of the open end of the garment

becomes objectionably flared and to avoid 65 this is the object of the contractile influence of the inwardly traversing holding members shown in this figure of the drawings.

Having thus described my invention, what I claim as new and desire to secure by Letters Patent, is:

1. The combination with a garment shaping and drying form of the character described, of vertically reciprocable means extending wholly about the base of the form 75 and carried thereby for holding the garment equally on all sides thereof.

2. The combination with a garment drying and shaping form of the character described, of a plurality of depressions about 80 the lower portion of the form, a plurality of holding means co-operatively engageable within the depressions and holding the garment from the inner side thereof.

3. The combination with a garment drying and shaping form of the character described, of a plurality of vertically disposed depressions in the outer face of the form adjacent the base thereof, said depressions being deeper at their upper ends, a vertically 90 reciprocable band around the form below the upper ends of the depressions, upstanding resilient holding members operative within the depressions, and means upon the resilient members for engaging and holding 95 the garment in position on the form.

4. The combination with a garment drying and shaping form of the character described, of a plurality of vertically disposed channels in the outer face of the form adjacent the base thereof, said channels being deeper at their upper ends, a vertically reciprocable band around the form below the upper ends of the channels, upwardly extending wires fixed to the band and registering within the channels, and garment engaging hooks formed on the upper ends of the wires and normally depressible within the deeper portions of the channels and thus freed from engagement with the garment on 110 the form when desired.

5. The combination with a garment drying and shaping form substantially as described, of depressible circumferentially contractile garment holding means about the 115 base of the form, whereby the sides of the garment are dried in a contracted state.

6. The combination with a garment shaping and drying form of the character described, of reciprocable means slidably carried against the base of the form and engaging the garment upon the interior for holding it equally upon all sides of the form.

7. The combination with a garment drying and shaping form of the character described, of a series of spaced depressions about the lower portion of the form, a band 125 slidably carried by the form below the de-

pressions and resilient members carried by the band which register with the depressions and engage a garment carried by the form alternately by the reciprocation of the band.

5 8. The combination with a garment drying and shaping form substantially as described having depressible garment holding means about the base of the form, of means whereby the opposite sides of the garment
10 engaged by the holding means are contracted

laterally in respect to each side and thus dried.

In testimony whereof I have hereunto affixed my signature in the presence of two witnesses.

EARL M. WITHERELL.
